UNITED STATES PATENT OFFICE

158,279

BOTTLE

Serge Heftler-Louiche, Paris, France, assignor to
 Societe a Responsabilite Limitee Parfums
 Christian Dior, Paris, France, a corporation of France

Application December 10, 1948, Serial No. 150,062

Term of patent 7 years

(Cl. D58—8)

To all whom it may concern:

Be it known that I, Serge Heftler-Louiche, a citizen of the United States, residing at Paris, France, have invented, a new, original, and ornamental Design for a Bottle, of which the following is a specification, reference being had to the accompanying drawing, forming part thereof.

In the drawing:

Fig. 1 is an elevational view of a bottle, showing my new design;

Fig. 2 is a top plan view thereof, and

Fig. 3 is a perspective view of the bottle with the closure cap removed from the base thereof.

I claim:

The ornamental design for a bottle, substantially as shown.
